UNITED STATES PATENT OFFICE.

REINHARD W. ELAND AND LARREL C. MILLER, OF PEORIA, ILLINOIS.

PISTON FOR GAS ENGINES.

Application filed November 28, 1927. Serial No. 236,121.

This invention pertains to pistons for internal combustion engines. An object is the provision of a type of piston whose upper portion, or that carrying the piston-rings is spaced from the body portion or skirt and separable therefrom whereby it may be removed from the cylinder for replacing or adjusting such rings and without "taking down" the entire engine as is usually the case.

Another object is to construct a piston having a ring-carrying portion and a skirt portion are spaced from one another for the purpose of both lightening the whole structure and reduce friction, as well as to minimize the feeding of oil to the piston ring portion.

Another object is to build a piston of spaced portions in skeleton form both to reduce weight, and that the oil instead of being carried too freely to the piston ring portion may more readily return to the crank-case.

Still another object is the provision of a body portion of an open skeleton structure, the skirt of which is severed at opposite positions and so constructed that it will automatically expand as it wears and prevent the well known "slap."

In addition to these objects the invention includes certain details of construction to be pointed out herein and form the subject of certain of the appended claims. As an assistance to the understanding of the invention the attached drawing is provided where-

in—

Figure 1 is an elevation in part section of the complete, assembled piston of our invention.

Figure 2 is a side elevation of a body portion including a skirt, the same being viewed from a different position from that in Figure 1.

Figure 3 is a plan of the said body portion.

The piston comprises two portions or sections designated by the characters 1 and 2. The portion 2 comprises a skirt 3 surmounted by a shell-like boss or extension 4 integral with said skirt and including lateral housings 5 bored to receive the usual wrist-pin 6 to which the connecting-rod 7 is clamped in customary manner. It is observed that said boss or extension 4 has an opening 8 extending well up into it, also that the top 55 of said skirt 3 is open at 9, 9 at opposite sides

of and outside the boss 4 and that it is severed at 10 at diametrically opposite sides, cutting into said openings 9.

Surmounting the boss 4 and lying thereon is the described portion or section 1 which includes the usual packing rings 11 and an "oil-ring" 12. A screw 13 is threaded through or screws into an opening 14 in the top of the boss 4 projecting beyond the same while the portion 1 has a central bore 15 through which the extremity of the screw passes when the said portion is seated in position, there being a nut 16 to engage the screw-end, the same being held from turning by means of a split key or cotter 17, for example, passing through said screw-end.

As commonly constructed pistons are of one piece or casting and when necessary to replace packing rings the oil pan must be removed from the crank-case and the connecting rod must be removed from its position on the crank-shaft in order to be enabled to withdraw the piston from the cylinder. This is laborious and required much time before the engine is again ready for use. 80 However, by the construction herein provided the mere withdrawal of the pin 17 and removal of the nut 16 permits the piston ring section to be removed, and only requiring that the engine head be dismounted.

We are aware that pistons have been made with split skirts but their forms have not been such that a wide limit of expansion was possible, besides which the wear thereon was necessarily uneven due to the length of the skirt and the form of the piston as a whole. 90 However, by constructing the body of the piston in a bifurcated form about as illustrated herein and providing a relatively short skirt portion which at the same time is severed at opposite sides in the manner shown the two portions of the said body can expand more or less under heat in practically a uniform manner. In practice it is our custom to make the skirt several thousandths of an inch oversize and by a suitable contracting tool it may be inserted into the cylinder and wearing more and more to a true fit, expansion occurring as wear continues. Since the whole body 2 is split well up into the boss 4 much latitude for expansion is allowed the said body, being so designed that all parts of the surface of the skirt can expand into intimate contact with the cylinder walls.

By having a separation of the two portions 1 and 2, if an excess of oil reaches the space between them it is caught by the upper surface of the skirt 3 and may pass back to 5 the crank-case, not shown, through the openings 9 and the places of separation at 10.

Another advantage arises from the form 10 of piston used in that there is less metal to retain heat and that what heat is taken up 15 by the portion 1 is rapidly carried down to the skirt portion 3 and conducted to the cylinder walls.

We claim:

1. A piston for internal combustion engines having a relatively short skirt portion, 15 spaced piston-pin bosses surmounting the same, the bores of the bosses for the piston-pin lying outward from the plane of said skirt portion, and an arched extension connecting the bosses, the whole being an integral structure, a piston-head separate from the named structure, spaced from said skirt portion and resting upon the arched extension and having a bore, a member 25 screwed into the extension projecting beyond the outer surface of the same and extending through the bore of said head, a nut engaging the member securing the head upon the extension, and means to fix the nut with respect to the member.

2. A piston for internal combustion engines having a relatively short skirt portion, 30 spaced piston-pin bosses from one side

thereof, the axes of the bores of said bosses being spaced from the plane of said side, 35 an extension arched across the space between the bosses, the same being integral with said bosses and having a substantially flat surface at its extremity lying in a plane paralleling the axes of said bores, a screw 40 engaging in the extremity and extending through it and beyond the flat surface thereof, a separate cupped head inverted upon the extension, the same being spaced from the skirt portion and having a surface complementary to said flat surface of the latter, resting thereon, and having a bore through which the screw extends, a nut engaging the screw and bearing upon the head securing the same upon the extension, and a pin 45 extending through the screw for fixing the nut with respect to said screw.

3. As part of a gas engine piston a relatively short skirt portion severed at substantially opposite positions and having spaced 55 piston-ring bosses erected upon the same outward from the plane thereof and whose bores lie outward from the surfaces carrying the bosses, and an arched extension connecting the bosses terminating at its end in a substantially flat surface, the whole being an integral structure.

In testimony whereof we affix our signatures.

REINHARD W. ELAND.
LARREL C. MILLER.
